UNITED STATES PATENT OFFICE.

LEONARD L. FERGUSON, OF CHICAGO, ILLINOIS, ASSIGNOR TO DUNTLEY PNEUMATIC SWEeper COMPANY, OF CHICAGO, ILLINOIS, A CORPORATION OF DELAWARE.

CLEANING DEVICE.

1,099,350.

Specification of Letters Patent.

Patented June 9, 1914.

Application filed October 6, 1913. Serial No. 793,630.

To all whom it may concern:

Be it known that I, LEONARD L. FERGUSON, a citizen of the United States of America, and a resident of Chicago, county of Cook, 5 and State of Illinois, have invented certain new and useful Improvements in Cleaning Devices, of which the following is a specification.

The objects of this invention are to provide a manually operative pneumatic sweeper with detachable sweepings and dust receptacles, while the brush is separately detachable from brush supports on the main body part of the machine. Thus, there is provided 10 a machine of this general type with a sweepings compartment separable from the machine, independently of the brush or any other mechanism liable to interfere with easy dumping of the sweepings compartment.

An illustrative embodiment of this invention is herewith shown in the accompanying drawings, in which—

Figure 1 is a side elevation of a pneumatic sweeper constructed according to this invention. Fig. 2 is a sectional view of the sweeper taken on the line A—A of Fig. 1.

The apparatus to which the present improvements are applied is shown and described in applicant's co-pending application for patent, Serial No. 739,169, filed December 30, 1912. The earlier application shows some features of general construction similar to the present one, the principal exception being that the brush is shown mounted on the detachable sweepings compartment. In the present case the brush is detachable from the main body part of the machine, but independently of the sweepings compartment.

Briefly stated, the apparatus comprises a main body part 1 in which are mounted a plurality of bellows 2 adapted to be successively operated to maintain a continuous suction while the device is in operation. The bellows 2 are actuated by pitman connections 3 with supporting wheels 4, and are adapted to draw air from the article being

cleaned through the suction nozzle 5 and to cause the air to pass through a suitable 50 dust collector 6. The nozzle 5 and a detachable sweepings compartment 7 are secured to the body part 1 by bail 8 pivoted to the latter and coöperating with spring clips 9 secured to the suction nozzle 5. Supporting 55 wheels 10 are journaled in the sweepings compartment 7 and are normally in driving engagement with rubber rollers 11 secured to a brush shaft 12. Secured to the ends of the brush shaft are pins 13 adapted to 60 pass through holes in bearing arms 14 secured to the base 15 of the body part 1. One or both of the arms 14 are preferably made of spring steel so that the brush may be easily removed. The sweepings compartment 65 is suitably cut away at 17 to permit the same to be moved vertically with respect to the brush shaft 12 which normally rests in said cut away portion as shown in the drawings.

In the operation of the device, the rotation of wheels 10 effects the desired rotation of the brush as in the usual carpet sweeper, the matter swept from the floor being brushed into the sweepings compartment 7. 70 To empty the sweepings compartment the bail 8 is swung upwardly around its pivots so that the said compartment may be removed. When the sweepings compartment is removed, the brush remains on the bracket 75 14 and therefore does not collect dust or interfere with the emptying of receptacle 7 in a manner possible when the brush is mounted on the latter.

Although but one specific embodiment of 80 this invention has been herein shown and described, it will be understood that some of the details of the construction shown may be altered or omitted without departing from the spirit of this invention as defined 85 by the following claims.

I claim:

1. In a carpet cleaning device, the combination with a body part, a brush rotatably mounted on said body part, a sweepings receptacle coöperating with said brush and de-

tachably mounted on said body part, and means carried by said sweepings receptacle for driving said brush.

2. In a carpet cleaning device, the combination with a body part, a brush rotatably and detachably mounted on said body part, a sweepings receptacle coöperating with said brush and detachably mounted on said body

part, and means carried by said sweepings receptacle for driving said brush.

Signed at Chicago this 3d day of October 1913.

LEONARD L. FERGUSON.
